UNITED STATES PATENT OFFICE.

HAROLD V. COES, OF NEW HAVEN, CONNECTICUT, ASSIGNOR TO THE SENTINEL MFG. CO., OF NEW HAVEN, CONNECTICUT, A CORPORATION.

HEAT-DISTRIBUTER FOR COOKING-COMPARTMENTS.

1,168,857.

Specification of Letters Patent.

Patented Jan. 13, 1916.

Application filed April 12, 1915. Serial No. 20,827.

To all whom it may concern:

Be it known that I, HAROLD V. COES, a citizen of the United States, residing at New Haven, in the county of New Haven 5 and State of Connecticut, have invented a new and useful Improvement in Heat-Distributors for Cooking-Compartments; and I do hereby declare the following, when taken in connection with the accompanying 10 drawings and the characters of reference marked thereon, to be a full, clear, and exact description of the same, and which said drawings constitute part of this application, and represent, in—

15 Figure 1 a view in front elevation of a cooking compartment of the type in which my improved heat-distributer is preferably used. Fig. 2 a view of the compartment in vertical central longitudinal section. Fig. 20 3 a view in vertical central transverse section, from front to rear. Fig. 4 a detached plan view of the distributer. Fig. 5 a detached view of the distributer in rear elevation on a reduced scale. Fig. 6 a corresponding view of the distributer in side elevation. Fig. 7 a detached reverse plan view of the baffle-plate showing its lower face provided with an equalizer.

My invention relates to an improvement 30 in heat-distributors for quasi fireless cooking apparatus of the type having ingress and egress draft passages, the object being to provide for the equalization of the heat throughout the cooking compartment.

35 With these ends in view my invention consists in the construction to be hereinafter described and pointed out in the claim.

As herein shown, my improved heat-distributer is rectangular in form and adapted 40 to perform the secondary office of a rack for food-trays. However, it is not essential to my invention that the device shall be adapted to perform the function of a rack for food-trays. As shown, the device consists 45 of a top 2, a back 3 and sides 4, being entirely open at the front. In dimensions it is adapted in size to be set in spaced relation within a rectangular cooking compartment 5 having double walls, filled as usual with 50 insulating material, the front of the compartment being closed by a double-walled insulated door 6 hung on hinges 7, furnished with a heat-indicator 8 and having a handle 9. The said distributer is made sufficiently smaller than the said compartment

to form a draft space 10 at each side of it, a draft space 11 above it, and a draft space 12 back of it. A draft space 13 is also formed between the open front of the distributer and the inner face of the door 6 60 of the cooking compartment 5 in which the distributer is positioned by means of outwardly turned flanges 14 at the lower ends of its sides 4 and back 3. Preferably the distributer is made removable from the compartment though this is not essential. The bottom of the distributer is formed by a removable, solid or imperforate baffle-plate 15 supported along its side edges by inwardly extending horizontal ledges 16 70 formed within the lower ends of the sides 4 of the distributer. At a point below the plane of the said baffle-plate 15, the back 3 of the distributer is formed with a horizontal series of ports 17 through which a 75 portion of the heated air is deflected by the baffle-plate 15 into the rear space 12 in which the heated air is diffused over the said back 3. At a point below the plane of the baffle-plate 15, the sides 4 of the distributer 80 are formed with corresponding ports 18 which, as shown, extend rearward from the center of the said sides 4. A portion of the heated air is deflected by the baffle-plate 15 through the ports 18 into the side spaces 10 85 in which it is diffused over the sides 4 and in which it rises over the top 2 of the distributer into the top air space 11. The said top 2 of the distributer is formed with a plurality of ports 19 from which the heated 90 air entering the inside of the distributer from the front space 13, escapes into the top space 11 above the same. All of the diffused currents into which the heated air is thus broken find their way ultimately to and 95 pass out through the egress draft-passage 20 which is furnished with a damper 21 operated as occasion may require by the lifting-rod 22 actuated by means forming no part of my present invention. Heated air is introduced into the compartment 5 at a point centrally below the baffle-plate 15, through an ingress draft-passage 23 formed in the bottom of the compartment. As shown a gas-burner 24 located directly below the 100 passage 23 is supplied with gas through a mixing pipe 25. However my improved distributer works equally well whether used in cooking compartments heated by gas or oil. As herein shown, I employ a heat-con- 105

server 26 mounted in a frame 27, whereby a space 28 is formed below the heat-conserver for the passage of the heated air laterally into a distributing chamber or space 29 located between the bottom of the compartment 5 and the baffle-plate 15 and receiving heated air through the inlet-passage 23 aforesaid.

As shown, my improved distributor is designed to perform the additional function of a rack for supporting food-trays or food-grids employed as occasion may require. For this purpose the sides 4 of the distributor are folded upon themselves to form two vertical series of inwardly projecting oppositely located horizontal ledges 30.

In the use of a cooking compartment having an ingress draft-passage and an egress draft-passage, the natural tendency is for the heated air to take the shortest course between the two passages, resulting in the stratification of the heat in layers, varying widely in temperature and detrimental to the cooking operation which is best carried on when the heat is the same in every part of the compartment. The amount of heated air passing through the respective ports and passages described is regulated by the size and number of ports and the size of the passages, all of which may be predetermined so that the heated air enveloping the distributor will be substantially equalized in temperature and speed of movement. The effect of my improved distributor is to equally heat all parts of the space reserved within the cooking compartment for the reception of the food.

As shown in Figs. 3 and 7, the baffle-plate 15 is provided upon the center of its lower face with a rectangular equalizer 31 pyramidal in its form in so far as it tapers in each direction from its center. The application of this equalizer to the bottom of the baffle-

plate forms a chamber 32 which is filled with suitable insulating material, such as asbestos. 45 The particular value of the construction just described lies in the use of the apparatus without the heat-conserver when the heat rises directly against the baffle-plate which, in the absence of the equalizer, would be 50 superheated at its center, endangering the burning of the contents of the cooking compartment. Obviously a conical equalizer might replace the rectangular pyramidal equalizer 31, this depending on the shape of 55 the cooking-compartment.

My improved device is not limited to use for cooking purposes, but might also be used for drying japanned articles, and in carrying on any other processes requiring heating 60 and drying.

I claim:—

In a cooking apparatus for conjoint fire and fireless cooking, the combination with an insulated cooking compartment having 65 an insulated front door, an egress draft-passage in its upper portion, and a burner-opening in its lower portion, of a closure for the said egress draft-passage, a burner co-acting with the said burner-opening, an open-front 70 removable heat-distributer smaller in size than the said compartment in which it is positioned to form air-spaces between its exterior surfaces and the interior surfaces of the said compartment, a baffle-plate mounted 75 in the lower end of the said heat-distributer for deflecting the heated air into the said air-spaces from which it reaches the said egress draft-passage, an equalizer centrally located upon the lower face of the said baffle-plate, and a heat-conserver adapted to be interposed between the said baffle-plate and the bottom of the said compartment and arranged over the burner-opening therein. 80

HAROLD V. COES.
